(57) CLAIM

The ornamental design for a tire mounting alignment pin, as shown and described.

DESCRIPTION

FIG. 1 is a left side elevational view of the tire mounting alignment pin of the present invention, the right side elevational view being a mirror image thereof;

FIG. 2 is a front elevational view of the tire mounting alignment pin of FIG. 1; and,

FIG. 3 is a rear elevational view of the tire mounting alignment pin of FIG. 1.

The top and bottom elevational views being substantially identical to FIG. 1.
